(57) **CLAIM**

The ornamental design for a grounding brush for a perforating gun, as shown and described.

DESCRIPTION

FIG. 1 is a front perspective view of a grounding brush for a perforating gun, showing the first embodiment of our new design in an environment of use.

FIG. 2 is a rear perspective view thereof, shown in an environment of use.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front perspective view of a second embodiment.

FIG. 10 is a rear perspective view thereof.

FIG. 11 is a front elevation view thereof.

FIG. 12 is a rear elevation view thereof.

FIG. 13 is a left side elevation view thereof.

FIG. 14 is a right side elevation view thereof.

FIG. 15 is a top plan view thereof; and,

FIG. 16 is a bottom plan view thereof.

In the drawings, the broken lines are for the purpose of depicting environment, and form no part of the claimed design.

1 Claim, 8 Drawing Sheets
